UNITED STATES PATENT OFFICE.

EDWIN LUNDGREN, OF FREDERICK, MARYLAND, ASSIGNOR TO COMBUSTION ENGINEERING CORPORATION, OF NEW YORK, N. Y., A CORPORATION OF NEW YORK.

UNDERFEED STOKER FURNACE.

Application filed September 9, 1922. Serial No. 587,050.

My invention relates to underfeed stoker furnaces, and has for its object to provide novel and improved means for preventing clinkers from forming on the side walls of such furnaces. It further has for its object to produce a novel construction in which the parts are easily renewable.

The several features of the invention will be clearly understood from the following 10 description and accompanying drawings, in which,

Figure 1 is a longitudinal sectional view, partly in elevation, with parts broken away and parts removed of an underfeed furnace embodying the features of the invention in their preferred form;

Fig. 2 is a sectional view taken on the line 2—2 of Fig. 1;

Fig. 3 shows detail side and front elevations of a tuyère block forming a component part of my improved construction;

Fig. 4 is a detail side elevation of an end tuyère structure forming another component part;

Fig. 5 is a detail sectional view partly in elevation, taken on the line 5—5 of Fig. 1;

Fig. 6 shows detail front, side and bottom views of an end tuyère structure forming another component part of my improved construction;

Fig. 7 shows detail side and bottom views of another component part; and

Fig. 8 is detail side and bottom views of still another component part.

The underfeed furnace illustrated in the drawings is of the multiple retort type with the outer wall 2 of the outer retort 4 spaced from a side wall 6 of the fire box of the furnace. In carrying out my invention I provide a supporting wall 8 corresponding to and arranged parallel with the outer retort wall 2 and adjacent to the fire box side wall. An angular shaped supporting member 10 is mounted on the upper edges of the walls 2 and 8 and is provided with an upright portion in the form of a rail 11 arranged adjacent the fire box side wall. The supporting member 10 extends substantially the length of the retort and is made in sections that are arranged end to end. Each section of the member 10 is held in position by means of a depending lug 12 on the base of said section which extends between the walls 2 and 8 (Figs. 1 and 2). Each lug 12 is provided with an aperture that re-

ceives the hooked end of an anchor bolt 13 which extends through an inverted U-shaped clamping member or yoke 14 having its ends abutting the under sides of inwardly turned flanges on the upper edges of the walls 2 and 8. This holding means for each section is located near the rear end of the section, except that the forward end section is provided with such means near both ends, the front end of each section other than the forward end section being securely held in position by an overlapping portion 16 of the next section in front thereof. Thus the several sections of the supporting member 10 are securely held in place and may be easily removed and replaced.

A row of tuyère blocks 18 is mounted on the supporting member 10. Each tuyère block is provided with an exposed wall 20, the lower end of which is turned inwardly 75 so as to abut a shoulder 22 on the base of said member 10. The base of said member 10 forms a ledge or dead plate which is provided with upstanding transverse reinforcing ribs 23. The upper end of the exposed wall 20 of each tuyère block is curved 80 outwardly to the fire box side wall. The portion of said exposed wall extending between the lower end thereof and said curved upper end portion is arranged in a vertical 85 plane and extends through and along the zone of clinker formation. Each tuyère block is provided with an outwardly projecting rib 24, the upper portion of which is provided with laterally projecting flanges 90 26 having their edges respectively in the planes of the edges of the exposed wall of the tuyère block. Means are provided that cooperate with the shoulder 22 to securely hold the tuyère blocks in position. As 95 shown, the upper edge portion of the rail 11 is offset inwardly to form a vertical flange 30 that interlocks with the wall of a transverse slot in the rib 24 of each tuyère block, the slot being provided with shoulders 32 that abut shoulders on the offset edge portion of the rail. With this construction, it will be apparent that the tuyère blocks can be removed and replaced only by sliding them longitudinally of the rail. 100

Tuyère structures 34 and 36 are arranged at the rear and forward ends, respectively, of the row of tuyère blocks. The tuyère structure 34 is mounted on a horizontal support 38 that constitutes a part of the support 110

for the overfeed grate bars (not shown). This tuyère structure is held in position by its forward edge wall abutting the rear wall of the last one of the row of tuyère blocks, and by a depending anchor lug 40 on its base being hooked under a shoulder on the support 38. The tuyère structure 34 is further provided with a vertical exposed wall 42 that is arranged in the plane of the vertical exposed walls of the tuyère blocks 18; an outer wall 44 which is spaced from the wall 42 and arranged adjacent the fire box side wall 6; and a closed rear end wall 46 connecting the walls 42 and 44.

15 The forward end tuyère structure 36 is provided with a vertical exposed wall 48 which is in the plane of the exposed walls of the tuyère blocks 18 and has its lower edge turned inwardly so as to engage the shoulder 20 22 on the supporting member 10. This structure is further provided with a closed front end wall 50 that extends from the forward edge of the exposed wall to the fire box side wall. The upper portion of the tuyère 25 structure 36 is provided with a depending outer wall 52 which is spaced from the exposed wall 48 and is arranged adjacent the fire box side wall. Two spaced bars 54 connect the lower end of the depending wall 52 30 and the exposed wall 48. These bars 54 are provided with transverse notches 56 on their under sides that are arranged to engage the flange 30 of the supporting rail 11 when the parts are assembled. The exposed wall 48 is 35 provided with spacing lugs 57 at its lower end for engagement with the rail 11. The tuyère structure 36 is detachably secured to the supporting member 10 by means of a depending lug 58 thereon having an aperture 40 that receives the hooked end of an anchor bolt 60, the lower end of which extends through an aperture in a cross bar 62 connecting the walls 2 and 8 and provided with a clamping nut 64 screw-threaded on 45 its lower end.

50 A lining 65 of asbestos is interposed between the structure as a whole and the side wall 6 of the fire box so as to form a flexible seal between the underfeed stoker and the side wall.

55 The adjacent front and rear edges of the exposed walls of the several tuyère blocks 18 and the tuyère structures 34 and 36 are provided with downwardly and inwardly inclined ribs 66 and grooves 68. The grooves 68 are wider than the ribs 66 and centrally receive the ribs so as to provide downwardly and inwardly inclined tuyère openings 70 leading from the interior of the blocks 18 60 into the firebox. The exposed walls of the tuyère structures 34 and 36 are provided with inwardly tapering tuyère openings 72; and the bases of the supporting member 10 and tuyère structure 34 are provided with 65 horizontal slots or grooves 74 that cooperate

with the upper edge of the outer retort wall 2 and the support 38, respectively, to form tuyère openings leading into the fire box.

From the foregoing it will be apparent 70 that the several tuyère blocks 18, tuyère structures 34 and 36 and supporting member 10 all cooperate to form an air chamber to which air may be supplied through the space between the walls 2 and 8, the air being directed into the fire box through the several tuyère openings so as to maintain the structure below a temperature which will cause damage to the same, to prevent the adhesion of clinkers and to promote combustion. The structure is of rigid, strong and durable construction and the component parts thereof may be easily assembled and taken apart. In case one or more of the vertical tuyère blocks should become broken 80 or burned, it may be easily replaced by removing the front end tuyère structure and sliding the blocks down to take the place of the broken one, the latter being previously broken off of its support. The exposed portion of the supporting member 10 forms a horizontal dead plate located at a point where it catches and supports burned out ash and so as to be protected from excessive heat, so that there is little danger of its being burned so as to require renewal. 90

As will be evident to those skilled in the art, my invention permits of various modifications without departing from the spirit thereof or the scope of the appended claims. 100

What I claim is:

1. An underfeed stoker furnace having, in combination, a fuel retort having its outer wall spaced from a side wall of the fire box of the furnace, a supporting wall 105 arranged adjacent said fire box side wall, a supporting member mounted on the upper edges of said retort wall and said supporting wall, and a row of tuyère blocks mounted on said supporting member and extending upwardly to a point on said side wall above the normal zone of clinker formation with the lower edges of their exposed faces spaced outward from the inner edge of said supporting member so as to form a dead plate 110 adjacent the exposed faces of said blocks, said supporting member and said row of tuyère blocks being in communication with the space between said retort wall and said supporting wall. 115

2. An underfeed stoker furnace having, in combination, a fuel retort having its outer wall spaced from a side wall of the fire box of the furnace, a supporting wall arranged adjacent said fire box wall, a supporting member having a base portion extending between the upper edges of said retort and supporting wall and having a vertical portion in the form of a rail arranged adjacent the fire box side wall and having its upper 125 portion 130

edge offset inwardly to form a vertical flange, and a row of tuyère blocks mounted on said supporting member each having a vertically depending portion engaging the outer side of said flange and each having the lower edge of its exposed face spaced a distance outward from the inner edge of said base portion.

3. An underfeed stoker furnace having, in combination, a fuel retort having its outer wall spaced from a side wall of the fire box of the furnace, a supporting member having a base portion extending between the upper edges of said retort wall and said fire box side wall and having an upwardly projecting portion in the form of a rail arranged adjacent to and longitudinally of said fire box side wall, and a row of tuyère blocks mounted on said supporting member having their exposed surfaces extending upwardly to a point on said fire box side wall above the normal zone of clinker formation, said tuyère blocks and rail portion of said supporting member having interlocking portions that are arranged to engage to hold the tuyère blocks on said supporting member and permitting them to be applied to and removed from said rail portion by sliding them longitudinally thereof, and each of said tuyère blocks having the lower edge of its exposed face spaced a distance outward from the inner edge of said base portion.

4. An underfeed stoker furnace having, in combination, a fuel retort having its outer wall spaced from a side wall of the fire box of the furnace, a supporting wall arranged adjacent said fire box side wall, a supporting member mounted on the upper edges of said retort wall and said supporting wall, a row of tuyère blocks mounted on said supporting member having their faces extending upwardly to a point on said fire box side wall above the normal zone of clinker formation, and tuyère structures at the ends of said row of tuyère blocks having their outer end walls extending to said fire box side wall and cooperating with said tuyère blocks to form an air chamber.

5. An underfeed stoker furnace having, in combination, a fuel retort having its outer wall spaced from a side wall of the fire box of the furnace, a supporting wall arranged adjacent said fire box side wall, a supporting member having a base extending between the upper edges of said retort wall and said supporting wall having a vertical portion in the form of a rail arranged adjacent said fire box side wall and having a shoulder on its base spaced inwardly from said vertical portion, a row of tuyère blocks mounted on said supporting member each having its exposed face arranged substantially in a vertical plane, having its lower end provided with a shoulder that abuts

against said upwardly extending shoulder on the base of said supporting member and having a portion that interlocks with the upper edge portion of said rail to cooperate with said shoulders to hold the block in position on said supporting member, and each of said tuyère blocks having the lower edge of its exposed face spaced a distance outward from the inner edge of said base.

6. An underfeed stoker furnace having, in combination, a fuel retort having its outer wall spaced from the side wall of the fire box of the furnace, a supporting member extending between the upper edge of said retort wall and said fire box side wall, and a row of tuyère blocks having the lower ends of their exposed surfaces spaced outward from the inner edge of said supporting member so as to form a dead plate between said exposed surface and said inner edge of the supporting member, said exposed surface having a vertical portion extending from said supporting member to a point above the normal zone of clinker formation and being curved upwardly and outwardly from said point to said fire box side wall.

7. An underfeed stoker furnace having, in combination, a fuel retort having its outer wall spaced from a side wall of the fire box of the furnace, a supporting member having its base mounted on the upper edge of said outer wall and extending substantially to said side wall of the fire box, and a tuyère structure comprising a row of tuyère blocks mounted upon said supporting member each having its exposed face arranged substantially parallel with said side wall and extending above the normal zone of clinker formation and having its lower edge spaced a distance outward from the inner edge of said base portion.

8. An underfeed stoker furnace having, in combination, a downwardly and rearwardly inclined retort having its outer wall spaced from a side wall of the fire box of the furnace, a tuyère structure extending from the upper edge of said outer wall of the retort to a point above the normal zone of clinker formation comprising a tuyère block arranged adjacent the lower end of the retort having a fuel supporting wall spaced from the adjacent side wall of the fire box and having an outwardly projecting wall extending to said side wall of the fire box and from the upper end of its forward edge to the lower end of its rear edge, a row of tuyère blocks arranged one against the other above the upper edge of said retort wall with the rearmost block engaging the forward edge of the fuel supporting wall of said end tuyère block, the tuyère blocks of said row being adapted to be moved in a direction parallel with the upper edge of said side wall of the retort and

being held from rearward movement by said rear end tuyère block, and a tuyère block removably mounted adjacent to the upper end of the retort having its fuel supporting face arranged in the plane of the fuel supporting faces of the tuyère blocks of said row and having its rear edge abutting against the foremost tuyère block so

that said tuyère blocks are held between the front and rear end blocks, said front end block having its front wall extending to the side wall of the fire box, and said tuyère blocks and said end blocks constituting one wall of an air passage arranged above said retort wall.

EDWIN LUNDGREN.
